(57) **CLAIM**

What is claimed is an ornamental design for a defibrillator display shield, as shown and described herein.

DESCRIPTION

FIG. 1 is a perspective view of a defibrillator display shield showing our new design;

FIG. 2 is a front view of the display shield shown in FIG. 1;

FIG. 3 is a side view of the display shield shown in FIG. 1;

FIG. 4 is a side view of the display shield shown in FIG. 1;

FIG. 5 is a top view of the display shield shown in FIG. 1; and,

FIG. 6 is a bottom view of the display shield shown in FIG. 1.

Broken lines in all drawing views are included for the purpose of illustrating portions of the defibrillator display shield that form no part of the claimed design.
